UNITED STATES PATENT OFFICE.

WILLIAM J. LEWIS, OF SYRACUSE, NEW YORK.

POWER PRESS IRONER.

Application filed December 24, 1926. Serial No. 156,896.

This invention relates to improvements in press ironer designed for use by laundries, tailors, and the like, and the invention relates particularly to improvements in the pressing device shown and described in my United States Patent No. 1,609,909, dated December 7, 1926.

The object of the invention is to provide a power operated pressing machine, which is heated as well as actuated by a common medium, as steam. A further object is to provide a novel construction and arrangement of the presser head, whereby, instead of being pivoted for rocking in a vertical plane towards and away from the top of the stationary buck and overhanging the buck at all times, the head is arranged to be moved bodily horizontally relatively to the buck, and the receding or releasing movement of the head being such as to enable the operator to freely apply, adjust and remove the clothes from the buck without interference from the displaced head, the distance the head may be moved away from the buck being sufficiently great to obviate all danger of the operator being burned by accidental contact with the heated movable pressing member, and the buck being entirely out of range of any shadow the head might cast, in case the machine is located in front of a window. A further object is to provide novel and simple means for first separating the head from the buck by moving it vertically, and then withdrawing the head horizontally towards the release position by a continuous mechanical operation, the return movement of the head being effected in a higher plane than the top of the buck, the lowering of the head to the pressing position and the final pressing of the garments being also effected by a continuous operation of the actuating members. And a further object is to generally improve and simplify the construction, arrangement and operation of clothes pressing or ironing machines of the class.

The various features and parts of the invention will be understood from the detailed description which follows, and by reference to the accompanying drawings, in which—

Figure 1 is a front elevation of the machine; showing the presser head in the ironing position. Fig. 2 is an end elevation of the same; showing by full and dotted lines the ironing and release positions of the movable parts. Fig. 3 is a top plan view, show-

ing the presser head withdrawn horizontally clear of the buck. And Fig. 4 is a rear side elevation of the machine. In all of the views several well-known parts not essential to the showing and describing of the novel features of the present invention have been omitted for clearness.

In the drawings, 2 represents a frame comprising an upright portion 2' having a yoked top 2^a and a forwardly extending horizontal bench 2^b, which is usually overlayed by a wooden table, as 2^c. 3 represents the usual buck, which is spaced from the table by a pedestal 3', the buck being heated preferably by steam supplied by pipe 3^a, and the exhaust or condensation being carried away from the buck, by a pipe 3^b.

4 represents the movable presser head, which may be of any suitable construction or pattern, the head being mounted upon the forward end of a horizontally arranged beam 5, to which it is secured by bolts 5'. The beam 5 is preferably disposed at right angles to the buck and head, and extends rearwardly between the arms of the yoke 2^a, by which the beam is supported. The beam 5 is preferably reciprocatable, and for this purpose, similar longitudinal grooves or ways 5^a are formed in its lateral edges, the said ways extending from the head to a point rearwardly of the yoke 2^a, as best seen in Fig. 2. The beam 5 is supported directly by guide-blocks 6, which are slideable in the ways 5^a, the said blocks being rigidly mounted in the split facing ends of short aligning shaft-sections 7, the latter being journaled in bearings formed in the arms of the yoke 2^a. By this arrangement, the beam 5 may be moved forwardly and backwardly freely upon the said guides, and the beam is also allowed a slight vertical teetering movement relatively to the stationary buck, as shown by the dotted lines in Fig. 2. When the head 4 is moved rearwardly from the buck 3, it is supported mainly by the frame portion 2'. The reciprocating and tilting movements of the beam and head, as well as the ironing pressure, are preferably effected by a fluid-pressure cylinder 8, through the actions of its piston 8', and piston-rod 8^a which rocks a lever 9, the said lever extending rearwardly through an opening 2^d in the frame 2', and being pivoted by a pin 9', to the said frame. To the rear end of lever 9 is pivoted an upright link or lever 10, whose upper end is slotted, as at 10', to receive and afford play for a pin 10^a,

which passes through the rear end of the beam 5, the said end preferably being slotted longitudinally centrally, as at 5^b (see Fig. 3), to receive the said lever. During the 5 reciprocation of the beam 5, the lever 10 simply plays loosely and idly in the slot 5^b without exerting either pull or pressure upon the pin 10^a. It is only at the extremes of the forward and backward strokes 10 of the beam, that pin 10^a engages the ends of the slot 10' (see Fig. 2). In practice, the slot 10' is preferably so calculated as to enable the levers 9 and 10 to effect the full ironing pressure of the head against 15 the buck before the piston 8' entirely completes its downward stroke. The forward and backward movements of the beam 5 are effected directly and positively by one or more bell-crank 12, which are pivoted by 20 a pin 12' to similar lugs 13' of a bracket 13, the latter being rigidly secured to the rear portion 2', by bolts 13^b (see Figs. 2 and 4). The bell-crank are provided with arms of unequal length, as 12^a—12^b, which connect 25 respectively with the lever 9 and to the opposite edges of beam 5. The arms 12^a extend rearwardly and are formed with slots 12^c. These arms are pivoted by a pin 12^a to the upper ends of links 14, whose lower ends are 30 pivoted to the lever 9, by a pin 9^a (see Fig. 2), the said connection being located between the frame and the rear end of said lever, and at a point that insures properly measured strokes of the beam. The upper 35 ends of arms 12^b of the bell-crank are formed with relatively long slots 12^c, which receive and afford the requisite play for a pin 5^c, that passes through a reduced portion 5^d of the beam 5. The arms 12^b are preferably resiliently connected to the beam, by a 40 spring 15 (see Fig. 2), the said spring preferably being of sufficient strength to normally lift and hold the head 4 a short distance above the buck, whenever the ironing pressure exerted by the lever 10 is relaxed. By 45 this arrangement, at the first slight pull of lever 9 and the links 14 upon the short arms 12^a, which action simultaneously breaks the pressing contact of lever 10 with the pin 10^a, the spring 15 instantly lifts the head 4 clear of the buck (see dotted lines at left in Fig. 2), and enables the bell-crank to move 50 the head rearwardly without disturbing the articles that have just been ironed. This 55 spring thereafter continues to exert its tension for tilting the beam, but the tilting is limited substantially to the initial lift of the head, by the resistance of the guides 6, as the beam moves towards the yoke 2^a, so that 60 the head, at the end of the release stroke, is positioned relatively to the buck, substantially as shown by the dotted lines in Fig. 2. The length of the slots 10' and 12^c are usually so calculated as to enable the levers 10 and 12 to maintain substantially the same

elevation of the head above the top plane of the buck at the extreme rearward movement of the beam, as that effected initially by the spring 15, as explained. This latter action is facilitated by the slight rotation of 70 the shaft-sections 7 in the bearings 2^a. By these latter provisions the full forward or return stroke of the beam and the head is effected substantially at the inclination, as shown in Fig. 2, the spring 15 again exerting its tension for holding the head clear of the buck until the final upward thrust of the lever 10 overcomes the said tension and effects the ironing pressure. By this peculiar arrangement the head returns to the ironing 80 position without disturbing the fresh articles that may be spread upon the buck. The head 4 is preferably heated by steam, by means of a swivel-joint pipe 16, which receives the steam from a cross 17, the said pipe thence passes through the yoke 2^a, and taps the head at 16'. The exhaust steam escapes from the head through a similar pipe 18, which discharges the waste fluid into a T 18', from which it may be returned to a 85 boiler or other destination, by a pipe 18^a. The exhaust carried from the buck by pipe 3^b may also be discharged into the T 18' (see Figs. 2 and 4). The performance of the 90 jointed portions of pipes 16 and 18 may be understood by consulting Figs. 2 and 4. The steam may be supplied to the cross 17 by a pipe 17'. The steam for operating the piston 8' flows from the cross 17, via a conductor 19', to a cock 19, which is operated by a lever 19^a, for alternately charging the top and bottom ends of the cylinder 8, in a well known manner. The exhaust from cylinder 8 may be effected by any suitable means (not shown). The cock 19 is usually operated by 100 a hand-lever, as 20, which is pivoted at 20' to the frame, and connects with the lever 19^a by a link 20^a. The lever 20 preferably traverses a slot 20^b formed in the bench 2^b and the table 2^c, as shown in Fig. 1.

By arranging the head to be moved horizontally away from the buck as herein shown and described, no part of the head overhangs the buck, and when the machine is located in front of a window, the full 115 day-light is thrown upon the buck, instead of the latter being more or less obscured by the shadow of the head, as heretofore. By moving the highly heated head horizontally away from the buck instead of tilting and 120 positioning the head at various angles relatively to the top of the buck, as heretofore, the operator's head is less affected by the heat radiated by the presser head, which 125 is very desirable.

Having thus described my invention, what I claim, is—

1. A power press ironer including a frame, a movable head and a stationary buck carried by the frame, a beam for sup-

porting the head, guiding means carried by the frame and movably supporting said beam, operating means, a bell-crank operated by said operating means, means connecting the bell crank with the beam for effecting longitudinal movements of the beam in a horizontal plane, and means connected to the operating means and to the beam for effecting the ironing pressure when the head is moved into registry with the buck.

2. A press ironer including a movable head and a stationary buck, a steam cylinder for operating one of said parts, a valve for controlling the steam, a support for the head, guides slidably engaging said support, means to pivotally mount said guides, means to move said support and said head toward and away from the buck in a horizontal plane, and tension means for separating the head from the buck in advance of the release stroke of said support.

3. In an ironer, a head, a buck, means to mount the head for tilting movement and for movement toward and away from the buck in a horizontal plane, pressure applying means connected to the head to hold the head in ironing position, means connected to the head to move the same in said horizontal plane, and means independent of said means to move the head in a horizontal plane connected to the head for tilting the latter from off the buck upon release of the pressure applying means and prior to said movement of the head in a horizontal plane.

35 4. In an ironer, a buck, a head, means to

mount the head for sliding and pivotal movement, means connected to the head for holding the latter in ironing position under pressure, head operating means, a bell crank connected to the head operating means for 40 sliding the head laterally away from the buck, and means connected to the head operating means and to the head for tilting the head from off the buck prior to sliding thereof.

5. In an ironer, a buck, a beam, a head connected to the beam, means to mount the beam for sliding and pivotal movement, pressure applying means connected to the head to hold the latter in ironing position, operating means for the head pivotally and 50 slidably connected to the beam to slide the latter, and means under tension coupled to the beam and to said operating means for tilting the head off of the buck upon release 55 of the pressure applying means and prior to said operating means sliding the head laterally away from the buck.

6. In an ironer, a buck, a head, means to mount the head for sliding and pivotal 60 movements, pressure applying means to hold the head in ironing position, means connected to the head for sliding the latter from off the buck, means connected to the head and to the sliding means for tilting the 65 head from off the buck prior to sliding of the head, and means to actuate the sliding means.

In testimony whereof I affix my signature.
WILLIAM J. LEWIS.
